UNITED STATES PATENT OFFICE.

WILLIAM TRETBAR, OF GERMANTOWN, PENNSYLVANIA.

HAT-PIN.

SPECIFICATION forming part of Letters Patent No. 781,574, dated January 31, 1905.

Application filed September 28, 1904. Serial No. 226,277.

To all whom it may concern:

Be it known that I, WILLIAM TRETBAR, a citizen of the United States, residing at Germantown, county of Philadelphia, and State 5 of Pennsylvania, have invented a certain new and useful Improvement in Hat-Pins, of which the following is a specification.

My invention relates to a new and useful improvement in hat-pins, and has for its object to provide a hat-pin which cannot be removed from the hat, but can be withdrawn from the hair, so that the hat may be removed.

With these ends in view this invention consists in the details of construction and combination of elements hereinafter set forth and then specifically designated by the claim.

In order that those skilled in the art to which this invention appertains may understand how to make and use the same, the construction and operation will now be described in detail, referring to the accompanying drawings, forming a part of this specification, in which—

Figure 1 is a sectional view of a portion of a hat, showing my improved hat-pin applied thereto; Fig. 2, a longitudinal section through a portion of the end of the hat-pin and the retainer; Fig. 3, an inside elevation of Fig. 2; Fig. 4, an elevation of the body portion of the 30 retainer; Fig. 5, an elevation of the retainer-plate.

A represents the hat-pin, the point of which is enlarged and pointed, as shown at A'.

B represents the body portion of the retainer, 35 which is in the form of a flat plate B', adapted to lie against the inside of the crown of the hat and be sewed thereto through the slots B² and B³. Of course instead of slots ordinary eyelet-holes might be used, if desired. C is a 40 tubular portion extending from the plate B', and this tubular portion extends inward from the crown of the hat, and the opening through the tubular portion is large enough to allow the enlarged portion A' of the pin to pass 45 through.

D is the retainer-plate, which is provided with slots D'. This retainer-plate is provided at the center with a buttonhole-slot E, and the enlarged portion of the buttonhole-slot E may 50 pass over the enlarged end of the pin A, and

then when the retainer-plate is slipped to one side the smaller portion of the buttonhole-slot will be behind the end A' of the pin, and thus the pin cannot be withdrawn from the retainer. The slots D' of the retainer-plate when in 55 this position will be in alinement with the slots B² of the plate B', and these two plates are then sewed through these slots to the crown of the hat, holding them rigidly in this position. It will thus be seen that while the 60 pin can be withdrawn from the hair sufficiently to allow the hat to be removed the pin cannot be withdrawn from the retainer, and thus there is no danger of losing the pins, as they always remain with the hat; but at any time 65 it is desired to change the pin this may be easily done by loosening the retainer-plate and slipping it to one side. Another advantage of this device is that there is only one opening made through the crown of the hat 70 for the hat-pin—that is, the opening through which the pin passes—and therefore the hat-crown is never marred and destroyed by innumerable holes, such as are made when ordinary hat-pins are used. When the pin is 75 withdrawn, the enlarged end proceeds into the tubular portion of the retainer, and thus the pin is prevented from catching in the hair as the hat is removed.

Of course I do not wish to be limited to the 80 exact construction here shown, as slight modifications could be made without departing from the spirit of my invention.

Having thus fully described my invention, what I claim as new and useful is— 85

In a device of the character described, a plate secured to the inside of the crown of the hat, a tubular guide extending through the crown of the hat and formed with said plate, a hat-pin extending through said tubular guide 90 and enlarged to a greater diameter at the point, the opening through the tubular guide and plate being large enough to admit of the passage therethrough of the enlarged point, a retaining-plate adapted to be secured upon 95 the inside of the other plate, said retaining-plate being provided with a buttonhole-slot, the enlarged portion of said buttonhole-slot being large enough to pass over the enlarged point of the pin, but the smaller portion of 100

the buttonhole-slot being smaller in width than the diameter of the enlarged point, said retaining-plate adapted to be secured in position with the larger portion of the buttonhole-slot out of alinement with the pin, as and for the purpose specified.

5 In testimony whereof I have hereunto af-

fixed my signature in the presence of two sub-scribing witnesses.

WILLIAM TRETBAR.
